Galph Burch
ATTORNEY.

UNITED STATES PATENT OFFICE.

LOUIS P. POWERS, OF PHILADELPHIA, PENNSYLVANIA.

HEADLIGHT.

Application filed May 28, 1923. Serial No. 641,990.

To all whom it may concern:

Be it known that LOUIS P. POWERS, citizen of the United States, residing at Philadelphia, in the county of Philadelphia and 5 State of Pennsylvania, has invented certain new and useful Improvements in Headlights, of which the following is a specification.

My invention relates to improvements in 10 headlights for automobiles and the like, the primary object of which is to provide a structure of novel design having as an integral part means adapted to eliminate the glare from the lighting element, so the beam 15 of light projected from the headlight will not be blinding to the drivers of automobiles and pedestrians approaching in the opposite direction.

A further object of the invention is to 20 provide a headlight of the above mentioned character which will sufficiently illuminate the roadway, the required distance, in front of the vehicle.

Another object of the invention is to provide 25 a headlight of the above mentioned character which is simple and durable in construction, composed of a few parts, efficient and reliable in performing its function, and inexpensive to manufacture.

30 Other objects and advantages of the invention will be apparent during the course of the following description.

In the accompanying drawing forming 35 a part of this specification and in which like numerals are employed to designate like parts throughout the same,

Figure 1, is a longitudinal cross sectional view of my improved headlight, and

Figure 2, is a perspective view of the 40 same showing the parts in separate relation.

In the drawing, wherein for the purpose of illustration I have shown a preferred embodiment of my invention the numeral 5, designates an elongated casing of substantially oval shape in cross section having a front circular opening 6, encircled by an annular screw threaded flange 7 and a dome 8 formed at its top. The bottom 9 of the casing is inclined upwardly towards the rear end 10 which is disposed above the center of the front opening 6. The dome 8 is provided with a downwardly inclined front wall 11 in alinement with the rear end 10 and which adjacent its jointure with the 55 flange 7 is provided with a depression 12

projecting slightly below the periphery of the flange. The rear wall 10 is provided with a central screw threaded aperture 13, to receive a removable lamp socket 14 which supports an incandescent lamp 15. Fitted 60 within the casing 5, in spaced relation, is a removable shell or reflector 19, conforming in shape to the casing and hence need not be specifically described. The rear end of the reflector has an opening 20 which fits 65 over the lamp socket 14, and the flange 21 has its edge bent reversely and outwardly forming the heading 22 and rim 23, the latter being normally seated on the lugs 24 projecting inwardly from the flange 7 of the 70 casing. These lugs are provided with pins 25 which fit in the V-shaped notches 25' cut at intervals in the rim 23, locking the reflector against revolving movement. An annular screw threaded ring 26 is threaded on 75 the flange 7 and carries a glass lens 27 held in place by clips 28. A packing cord 29 is placed between the ring 26 and the rim 23 whereby the latter is held securely in 80 place. The casing is equipped at each side 85 with an apertured lug 30 to receive the arms 31 of the usual bracket 32 mounted on the vehicle. When assembled the lamp 15 will be in alinement with the inclined wall 33 of the dome 34 of the reflector, as clearly shown in Figure 1.

In use, it can be readily seen that by reason of the peculiar construction of the reflector, the wall 33 of the dome 34 is in direct alinement with the lighting element 90 15 whereby the glare is eliminated from the light rays before being projected onto the roadway. A headlight of this construction will avoid accidents caused by glaring headlights which are blinding to drivers of 95 machines approaching in the opposite direction. It will not require the use of special non-glare lens and hence will not reduce the beam of light thrown in front of the machine. The design of the casing is neat and 100 attractive and is so shaped it may be cast in one piece.

It is to be understood that the form of my invention herewith shown and described is to be taken as a preferred example of the 105 same, and that certain changes in the shape, size and arrangement of parts may be resorted to without departing from the spirit of the invention or the scope of the subjoined claims.

Having thus fully described my invention, what I claim is:—

1. In a headlight, the combination of an elongated casing and reflector of substantially oval shape in cross section, each having a front circular opening disposed on a vertical plane and surrounded by an annular flange, a bottom wall inclined upwardly towards the back wall which is disposed
- 10 above the center of said opening and a top wall disposed on a horizontal plane above the peripheral edge of said opening, said top wall having its forward portion inclined downwardly adjacent said opening connecting the top wall with said flange and forming a shield within said casing to the rear of said opening and an incandescent light mounted in the back and adjacent the top wall of said reflector in alignment with said shield.
- 15 2. In a headlight, the combination of a casing, a reflector removably mounted in

said casing, said casing and reflector each having a front opening surrounded by an annular flange, a bottom wall inclined upwardly towards the back wall which is disposed above the center of said opening and a top wall disposed on a horizontal plane above the peripheral edge of said opening, said top wall having its forward portion inclined downwardly at its jointure with said flanges, a plurality of spaced lugs extending radially from the inner periphery of the flange of said casing having pins passing therethrough, a rim extending laterally from the flange of said reflector adapted to seat on said lugs and having a plurality of spaced notches to fit over said pins, said lugs and pins spacing said reflector from the casing and preventing rotary movement thereof, and a clamping ring secured to said casing and bearing against said reflector.

In testimony whereof I affix my signature.
LOUIS P. POWERS.
